UNITED STATES PATENT OFFICE.

JOHN P. DORAU, OF JEFFERSON, WISCONSIN.

WASHING-MACHINE.

1,215,501.

Specification of Letters Patent. Patented Feb. 13, 1917.

Application filed October 25, 1915. Serial No. 57,683.

To all whom it may concern:

Be it known that I, JOHN P. DORAU, a citizen of the United States, and resident of Jefferson, in the county of Jefferson and State of Wisconsin, have invented new and useful Improvements in Washing-Machines, of which the following is a description, reference being had to the accompanying drawings, which are a part of this specification.

The invention relates to washing machines.

The invention is designed more particularly to provide a new and improved means for simultaneously pounding and agitating the clothes and means for operating said pounder and agitator.

In practice the usual pounder operates to force air into the clothes on its downward stroke and thus drive the water downward through them and on its upward stroke to suck the air driven into the clothes from them and thus draw the water upward through them.

The present invention has for its object to provide a pounder which operates somewhat different from the ordinary pounder in that on its downward stroke it forces air and water into and through the clothes and on its upward stroke by reason of a valve within it air is permitted to enter into the pounder above the clothes and thus prevent any suction or vacuum tendency of the pounder to carry the clothes upward with it and to draw the water and dirt backward through the clothes.

The invention is further designed to provide an agitator for the clothes consisting of a plurality of blades pivotally secured to the shaft upon which the pounder is mounted.

The invention is further designed to provide mechanism for imparting a vertically reciprocating motion to the pounder during an alternately reversed horizontally oscillating motion of said pounder.

The invention further consists in the several features hereinafter set forth and more particularly defined by claims at the conclusion hereof.

In the drawings Figure 1 is a vertical sectional view of the device embodying the invention;

Fig. 2 is a detail sectional view taken on the line 2—2 of Fig. 1;

Fig. 3 is a detail sectional view of a modified form of combined pounder and agitator;

Fig. 4 is a detail view of another modified form of combined pounder and agitator;

Fig. 5 is a detail plan view of a modified form of pounder.

In general, the washing machine consists of a tub or clothes receptacle 6 of usual construction, a vertically disposed shaft 7 journaled in the cover 8 of said tub, mechanism for operating said shaft, and a combined pounder and agitator mounted on said shaft.

The mechanism for operating the shaft 7 consists of a segmental gear 9 mounted on an oscillating lever 10 journaled on a shaft 10' mounted on a bracket 11 secured to the tub 6, a bevel gear 12 in mesh with the gear 9 and mounted on a shaft 13 journaled in a bracket 14 on the cover 8 and a driving connection between said shaft 13 and the shaft 7. The driving connection consists of a collar 15 provided with an extension 16 having a bore therein in which the enlarged rounded end 17 of the shaft 13 is slidably and rotatably mounted. The end 18 of the shaft 13 is angularly inclined with respect to that portion journaled in the bracket 14 and when the shaft 13 is alternately reversely rotated through the gears 9 and 12 it will, through the driving connection just described, impart a vertically reciprocating and alternately reversed horizontally reciprocating movement to the shaft 7.

Means are provided for imparting the necessary momentum to the operating mechanism comprising a fly-wheel 19 removably mounted on a shaft 20 secured to the bottom of the tub and carrying a gear 21 which is in mesh with a gear 22 also revolvably mounted on the bottom of the tub and means connecting said gear 22 with the operating lever 10 to continuously rotate said gear and fly-wheel 19. This connecting means consists of a pitman 23 pivotally and eccentrically connected at one end to the gear 22 and pivotally connected at the other end to the lower end of a lever 24 which is pivotally connected intermediate its ends to a bracket 25 mounted in the side of the tub and which is slidably and pivotally connected at its upper end with the lever 10 by a connection consisting of an enlarged rounded end 26 and a cylindrical bore 27 forming a part of the lever 10. As a result of this connection between the lever 10 and the fly-wheel 19, the oscillation of the lever 10 will impart a continuous rotation to the fly-wheel which will provide sufficient momentum for the operating mechanism so as to insure its proper operation.

Having described the machine in general and the mechanism for operating the vertical agitator and pounder shaft 7, the combined pounder and agitator will now be described.

In general, the combined pounder and agitator consists of a pounder 28 operatively secured to the shaft 7, a valve for permitting air to enter within the pounder on its upward stroke to prevent a vacuum being formed within the pounder and an agitator consisting of a plurality of blades 29, having rounded ends and pivotally connected to ears 29' on the pounder.

In Figs. 1 and 2 the pounder consists of an open bottom casing having a pair of oppositely extending wing portions 30, side walls 31, an enlarged rounded bottom edge 32, and a hub member 33 journaled on the shaft 7 secured thereon by a pin 34 secured to the shaft and disposed between the ears 29' of the pounder.

It will be noted that this pounder differs from the usual form of cone-shaped pounder in that the wings 30 have outer rounded ends 31' which are of greater width than the medial portions adjacent the shaft 7. The advantage of a pounder of this shape is that the greater part of the air within the pounder is confined at the outer ends and these outer ends constitute the main working portions of the pounders and engage a greater bulk of the clothes, than the ordinary construction of pounder as the greater part of the clothes are disposed between the center and the sides of the tub. The result of this construction then is that the greater part of the washing is done at the outer ends of the pounder upon the greater bulk of the clothes and consequently its operation is more efficient than the usual construction of pounder which operates in the center of the tub upon the least bulk of the clothes. The valve in this construction consists of a plurality of inclined bores 35 communicating with the interior 36 of the casing and with a conical valve seat 37 in the upper part of said member 33 and a conical valve head 38 mounted on the shaft 7 is adapted to move against said seat and close the openings of the bores 35 thus shutting off any passage of air from the interior of the pounder through said openings on the downward stroke, but permitting the raising of the valve 38 from its seat 37 on the upward stroke, the hub member 33 being of less length than that portion of the shaft 7 between the collar 34 and the valve head 38. The ears 29' to which the blades 29 are pivotally connected by a shaft or pin 39 are integral with the hub member 33.

In Fig. 3 I use the same kind of pounder casing but employ a modified construction of valve. In this instance the pounder casing is provided with a hub member 40 hav-

ing a plurality of inclined bores 41 meeting at their lower ends and communicating with the interior of the pounder through a central aperture 42 which has a conical valve seat 43 adapted to be engaged by the conical end 44 of the shaft 7 to shut off communication from the outside with the interior of the pounder through the opening 42, the shaft 7 being journaled in a threaded portion 48 of the hub member which is in threaded engagement with an interiorly threaded cap 49 in which the shaft is also journaled. A pin is slidably but non-rotatably mounted in a diametrically extending slot 50' in the portion 48, the slots 50' providing for a limited sliding movement of the pin and shaft with respect to the member 40 which permits the movement of the shaft 7 to open and close the aperture 42. The blades 29 are connected to the member 40 by ears 29' and shaft 39.

In Fig. 4 I use the same kind of pounder casing with a modified construction of valve. In this instance the pounder casing is provided with a central aperture 51 and with screws 52 mounted in the top of the casing and projecting upwardly therefrom. The shaft 7 is provided with an annular flanged member 53 which is provided with apertures 54 in which the stems 55 of the screws 52 are slidably mounted. The top of the casing adjacent the aperture 5 forms a flat valve seat 56 and the bottom of the member 53 is flat and flush with the ends of the shaft 7 to form a flat valve head to shut off communication between the interior and exterior of the pounder through the aperture 51. The blades 29 are pivotally connected to the pounder by ears 29' and shaft 39.

In Fig. 5 I have shown a modified form of pounder casing in which I employ three radially extending wings 57 which may be used in place of the two winged pounder casing and which would, of course, necessitate a separate pivotal connection for the blades 29 of the agitator.

The operation of the device may be briefly described as follows:—

On the downward movement of the shaft 7, when the pounder engages the clothes, the shaft 7 moves downwardly with respect to the pounder and thus closes the valve and the air and water in the pounder is forced into and through the clothes thereby forcing the air and water through them and the dirt out of them. On the upward stroke the first movement of the pounder shaft opens the valve and permits air to enter within the pounder thus preventing any suction or vacuum action of the pounder in drawing the clothes upwardly and the water and dirt backwardly through them and permitting the pounder to move up free of the clothes. Thus when the pounder is engaging the clothes, the first movement of the pounder

shaft causes the opening or closing of the pounder valve. Thus also the combined operation of the pounder operates to drive the air and water through the clothes to clean them and at the same time the horizontal oscillation of the pounder shaft moves the pounder, which is slidably but non-rotatably connected thereto, to engage a different portion of the clothes in the tub.

10 The invention thus exemplifies a washing machine in which the pounder is provided with an automatically operating air-valve and also one in which the agitator is connected to and operable with the pounder.

15 The invention is not to be restricted to the details of construction herein set forth, but it is to be understood that the construction may be varied so long as it is within the scope of the appended claims.

20 What I claim as my invention is:—

1. In a washing machine, the combination, with a vertically and horizontally reciprocated shaft, of a pounder slidably mounted on said shaft to turn therewith, and a valve operating automatically to admit air to the pounder on its upward movement and to exclude air therefrom when the pounder strikes the clothes.

2. In a washing machine, the combination, with a vertically and horizontally reciprocated shaft, of a pounder mounted on said shaft to turn therewith and provided with an opening in its top, and means fixedly carried by said shaft operable to close said opening on the downward movement of the shaft and to open the same on the upward movement thereof for the purpose described.

3. In a washing machine, the combination, with a pounder shaft, of a pounder comprising an open bottom casing, and agitator

blades pivotally mounted within the hollow of said casing.

4. In a washing machine, the combination, with a vertically and horizontally reciprocated shaft, of a pounder vertically slidably movable with respect to said shaft and connected to turn therewith comprising an open bottom casing having an opening in its top and a valve fixedly carried by said shaft and operated thereby to open and close said opening.

5. In a washing machine, the combination, with a vertically reciprocated shaft, of a pounder vertically slidably connected to said shaft comprising an open bottom casing having an opening in its top, a valve carried by said shaft and operated thereby to open and close said opening, and a plurality of agitator blades pivotally mounted within the hollow of the pounder casing.

6. In a washing machine, the combination, with a vertically reciprocated shaft, of a pounder slidably but non-rotatably connected to the lower end of said shaft and provided with an opening in its top and having a valve seat adjacent said opening, and a valve head on the lower end of said shaft cooperating with said valve seat.

7. A clothes pounder comprising a movable shaft, a valve member fixedly mounted on the lower end thereof and provided with apertures, a pounder comprising an open bottom casing having an opening in its top and a valve seat disposed adjacent said valve member, and fastening means secured to the pounder and slidably mounted in the apertures in the valve member.

In testimony whereof, I affix my signature.

JOHN P. DORAU.
